ENGINE

Andre J. Meyer, Detroit, Mich., assignor to Continental Motors Corporation, Detroit, Mich., a corporation of Virginia

Application September 11, 1931, Serial No. 562,280

24 Claims. (Cl. 123—81)

My invention relates to internal combustion engines and more particularly to engines of the sleeve valve type.

In connection with internal combustion engines of the sleeve valve type and in particular with engines employing a single sleeve valve of the type having a combined reciprocating and oscillating movement relative to the cylinder and sleeve axes, it is found desirable to provide a maximum intake port area at the beginning of the engine intake cycle in order to realize full advantages of its possibilities and to provide an engine of maximum efficiency and which will develop maximum power.

An object of my present invention is to construct an engine wherein improved engine performance will be obtained by providing larger intake port areas at the beginning of the engine intake cycle.

Another object of this invention is to construct the sleeve valve engine having generally improved operating characteristics by providing increased intake port areas for permitting a larger volume of fuel mixture to be introduced into the engine cylinder for each engine cycle.

It is possible to accomplish the objects as specified above by increasing the rapidity at which the intake port opens and this is preferably accomplished in the illustrated embodiment of my invention by constructing cooperating engine elements and timing the actuation of the valve means as to obtain a greater engine intake area at or near the beginning of the engine intake cycle.

For a more detailed understanding of my invention, reference may be had to the accompanying drawing which illustrates one form which my invention may assume, and in which:

Fig. 1 is a vertical transverse sectional view through an engine of the sleeve valve type constructed in accordance with my invention,

Fig. 2 is a horizontal plan sectional view taken substantially on the line 2—2 of Fig. 1,

Fig. 3 is a diagrammatic view graphically illustrating the increased intake port area which can be obtained with a sleeve valve engine as constructed in accordance with my invention,

Fig. 4 is a diagrammatic view graphically illustrating the exhaust valve area of the engine,

Fig. 5 is a diagrammatic view graphically illustrating the relationship between the intake and exhaust ports of an engine of the sleeve valve type, and

Fig. 6 is a view of a typical cylinder showing one form of sleeve valve drive whereby to impart a

combined reciprocating and oscillating motion to said valve.

In the preferred embodiment of my invention as illustrated in the accompanying drawing I have illustrated an engine which is provided with an engine block 10 having a cylinder 11 and a cylinder head 12 secured to the engine block. The cylinder head provides a combustion chamber 13 preferably within the depending portion 14 which depends within the cylinder and spaced from the walls thereof to provide a sleeve pocket 15 adapted to accommodate the upper end of a sleeve valve means 16. It is obvious that any type of sleeve valve means may be employed with the engine, but in order to illustrate the invention I have chosen a sleeve valve means of the Burt-McCollum type wherein a single sleeve is given a combined reciprocating and oscillating movement with respect to the cylinder and sleeve axis and in which any point on the sleeve traverses a closed path. Any suitable means may be provided for actuating the sleeve valve means.

The cylinder is provided with an intake port 17 and an exhaust port 18, the sleeve being provided with intake and exhaust ports 19 and 20 respectively cooperating with the cylinder intake and exhaust ports. A piston 21 is cooperatively associated with the cylinder and preferably reciprocates within the sleeve 16, this piston being adapted to be connected with the engine crank-shaft (not shown) by means of a connecting rod 22. The piston is operated in a manner which causes the same to over-travel the said cooperating sleeve and cylinder ports when the same reaches the outermost position of its travel and preferably the same is so arranged as to provide a minimum of clearance between the top of the piston and the lower face of the re-entrant cylinder head when the piston is at outer or top dead center.

Heretofore the sleeve valve means have been actuated in a manner as to open the cylinder intake port at or near the time when the piston reaches top dead center and the curve A (see Fig. 3) graphically illustrates the amount of valve area obtained with normal valve timing, this curve being plotted against crank angle. One means of obtaining an increased valve area is by advancing the time at which the cooperating cylinder and sleeve intake ports come in registration or begin to overlap so as to open the cylinder intake port well in advance of the normal valve opening. The curve B graphically illustrates the valve area as plotted against crank angle which is obtained by an early valve timing.

Under normal operating conditions such an early valve timing is impractical to use because of the fact that the exhaust port is open and an excessive amount of overlapping of the intake 5 and exhaust of the fuel mixture introduced into the engine cylinder is not permissible. In order to realize the advantages of increased intake port area by employing an early valve timing, means have been provided for masking the intake port 10 so as to prevent the introduction of fuel mixture into the engine cylinder until the exhaust port is closed or nearly so. In other words, I have provided means for opening the cylinder intake port prior to the engine intake so as to provide a maximum of opening at the initial portion of the 15 engine intake. In the present embodiment of my invention this is accomplished by operating the engine piston in such a way as to cause the piston to over-lap the open cylinder and sleeve intake ports, and preferably the top of the piston as the same moves outwardly of the cylinder during the exhaust cycle is so located with respect to the sleeve intake ports as to preferably over-lap the entire port opening. As the opening increases 20 the piston is preferably moving outwardly in advance of the opening. Thus after the piston reaches the outer or top dead center and begins to travel inwardly of the cylinder the intake ports are uncovered rapidly by the piston and the intake valve area is very rapidly increased 25 with respect to the area obtained with normal valve timing. The shaded area in Fig. 3 graphically represents the gain in valve area resulting from the use of an early valve timing and co-operating piston. Curve D graphically represents the piston travel.

By reason of the construction as described above I have been able to materially increase the intake valve area and to make it possible to obtain a greater volume of fuel mixture in the cylinder for each engine cycle. A direct result from increasing the volume of fuel mixture introduced into the cylinder is that an increased power is obtained.

In the construction herein illustrated I have provided a piston which over-laps the intake ports and so cooperates with the sleeve valve means as to control the engine intake. It was noticed however, that when the piston over-travelled the intake ports it also over-travelled the exhaust ports a like amount and it was found that a certain percentage of exhaust gases were trapped within the engine cylinder and unless these exhaust gases were removed in some manner they prevented the introduction of the maximum amount of intake gases. In Fig. 4 the exhaust valve area is graphically illustrated by the curve C, D' illustrating the curve representing piston travel and the amount of exhaust gases trapped within the engine cylinder is represented by the shaded area in this figure. In order to provide means for exhausting the engine cylinder during the time the intake cylinder port is opened and before the engine intake takes place I have provided a cut-away portion 30 in the piston which is so arranged as to be located adjacent to the exhaust ports and to prevent the piston from covering the exhaust ports during this portion of the piston travel. It will thus be noted that with the construction as above described, there is no exhaust gases trapped within the engine in excess of the normal amount which is trapped within the combustion chamber 13 as in the usual engine. Due to the slight over-lapping 70 of the engine intake and engine exhaust most

of the exhaust gases trapped within the combustion chamber are swept out by the incoming gases and the operation of the piston as illustrated herein is such as to prevent any of the exhaust gases being compressed by the outwardly travelling piston. Thus as the engine intake opens a maximum amount of fuel mixture may be taken into the cylinder thereby realizing to the fullest extent the advantages made possible by the advancing of the valve timing.

In Fig. 5 the relationship between the intake and exhaust cylinder and sleeve ports are illustrated and it will be noted that the cylinder intake port is opened to a considerable extent before the exhaust valve is closed. It is noted that the construction as herein described and illustrated provides an engine of improved operating characteristics due primarily to the fact that an increased intake port area is obtained while still maintaining the over-all size of the engine at a minimum. The sleeve valve engine of the type developed by applicant has proved to have improved operating characteristics as compared with other types of engines and the additional improvement as described and illustrated herein has further improved the operating characteristics.

Although I have illustrated but one form of my invention, and have described in detail but a single application thereof, it will be apparent to those skilled in the art to which my invention pertains that various modifications and changes may be made therein without departing from the spirit of my invention or from the scope of the appended claims.

What I claim as my invention is:

1. In an engine of the sleeve valve type having a cylinder ported for intake and exhaust, a piston operable in said cylinder, sleeve valve means controlling said ports, said sleeve valve means opening said cylinder intake port prior to engine intake and prior to the time when said piston reaches its outermost position of travel, and means cooperating with said sleeve valve means for controlling the engine intake, said sleeve valve means cooperating with said cylinder exhaust port to provide for engine exhaust during said opening of said cylinder intake port and prior to engine intake.

2. In an engine of the sleeve valve type having a cylinder ported for intake and exhaust, sleeve valve means controlling said ports, a piston cooperating with the cylinder, said sleeve valve means opening said cylinder intake port prior to engine intake and prior to closing said cylinder exhaust port, said piston cooperating with the sleeve valve means for controlling the engine intake and provided with means providing for engine exhaust during the opening of said cylinder intake port and prior to engine intake.

3. In an engine of the sleeve valve type having a cylinder ported for intake and exhaust, sleeve valve means controlling said ports, a piston co-operating with the cylinder, said sleeve valve means opening said cylinder intake port prior to engine intake and prior to closing said cylinder exhaust port, said piston cooperating with the sleeve valve means for controlling the engine intake and having a cut-away portion providing for engine exhaust during the opening of said cylinder intake port and prior to engine intake.

4. In an engine of the sleeve valve type having a cylinder ported for intake and exhaust, sleeve valve means having intake and exhaust ports adapted for cooperation with said cylinder

- intake and exhaust ports, said sleeve valve means opening said cylinder intake port prior to engine intake, and a piston cooperatively associated therewith and arranged to overlap said sleeve intake port during a portion of the time when said sleeve intake port is in registration with the cylinder intake port whereby to control the engine intake, said piston having means providing for engine exhaust during the opening of the cylinder intake port and prior to engine intake. 5

5. In an engine of the sleeve valve type having a cylinder ported for intake and exhaust, sleeve valve means having intake and exhaust ports adapted for cooperation with said cylinder intake and exhaust ports, said sleeve valve means opening said cylinder intake port prior to engine intake, and a piston cooperatively associated therewith and arranged to overlap said sleeve intake port during a portion of the time when said sleeve intake port is in registration with the cylinder intake port whereby to control the engine intake, said piston having a cut-away portion cooperating with said sleeve exhaust port to provide for engine exhaust during the opening of the cylinder intake port and prior to engine intake. 10

20 6. In an engine of the sleeve valve type having a cylinder ported for intake and exhaust, sleeve valve means having intake and exhaust ports adapted for cooperation with said cylinder intake and exhaust ports, said sleeve valve means opening said cylinder intake port prior to engine intake, and a piston cooperatively associated therewith and arranged to overlap said sleeve intake port during a portion of the time when said sleeve intake port is in registration with the cylinder intake port whereby to control the engine intake, said piston having a cut-away portion adjacent the top thereof adapted for registration with said sleeve exhaust port to provide for engine exhaust during the opening of the cylinder intake port and prior to engine intake. 25

30 7. In an engine of the sleeve valve type having a cylinder ported for intake and exhaust, said cylinder intake and exhaust ports located in substantially a common plane extending substantially perpendicular to the cylinder axis, sleeve valve means having intake and exhaust ports adapted for cooperation with said cylinder intake and exhaust ports, said sleeve valve means opening said cylinder intake port prior to engine intake; and a piston cooperatively associated therewith and arranged to overlap said sleeve intake port during a portion of the time when said sleeve intake port is in registration with the cylinder intake port whereby to control the engine intake, said piston having means providing for engine exhaust during the opening of the cylinder intake port and prior to engine intake. 35

40 8. In an engine of the sleeve valve type having a cylinder ported for intake and exhaust, sleeve valve means of the combined oscillating and reciprocating type ported for intake and exhaust and controlling said cylinder ports, said sleeve valve means opening said cylinder intake port prior to engine intake and while said engine is still exhausting, and means cooperating with said sleeve valve means for masking said sleeve intake port during the first portion of the intake opening period whereby to control the beginning of engine intake. 45

50 9. In an engine of the sleeve valve type having a cylinder ported for intake and exhaust, sleeve valve means of the combined oscillating and reciprocating type controlling said ports, said

55 sleeve valve means opening said cylinder intake port prior to engine intake and while said engine is still exhausting, and means cooperating with said sleeve valve means for controlling the cylinder intake port prior to engine intake and while said engine is still exhausting, and means cooperating with said sleeve valve means for controlling the initial opening of the engine intake. 50

60 10. A piston for a sleeve valve engine having a cylinder ported for intake and exhaust and sleeve valve means for controlling said cylinder ports, said sleeve valve means adapted for opening said cylinder intake port prior to engine intake, said piston comprising a structure having a cut-away portion cooperating with said cylinder exhaust port whereby to provide for engine exhaust during the opening of said cylinder intake port and prior to engine intake. 85

65 11. In an internal combustion engine of the sleeve valve type, a cylinder ported for intake and exhaust, sleeve valve means ported for intake and exhaust and controlling said ports, a cylinder head provided with a portion depending within the cylinder and spaced therefrom to provide a sleeve pocket for receiving the upper portion of said sleeve valve means, and a piston cooperating with the cylinder and adapted for travel in such a manner as to substantially cover said ports during the latter portion of the engine exhaust cycle to control engine intake, said piston having means providing for engine exhaust during the latter portion of the opening of the cylinder exhaust port and substantially prior to the engine intake. 90

70 12. In an engine of the sleeve valve type having a cylinder ported for intake and exhaust, sleeve valve means controlling said ports, and a piston cooperating therewith and constructed to overlap said sleeve ports during a portion of its operation, said piston provided with a cut away portion cooperating with the sleeve exhaust port to provide for engine exhaust while said piston is positioned in overlapping relation with the said intake port. 100

75 13. In an engine of the sleeve valve type having a cylinder ported for intake and exhaust, sleeve valve means associated therewith for controlling said ports, whereby to control the cyclical events of the engine, and a piston movable outwardly of the cylinder to a point at least in line with the outer edge of a sleeve port when in registry with an associated cylinder port, said piston having a cut-away portion cooperating with said sleeve port. 110

80 14. In an engine of the sleeve valve type having a cylinder ported for intake and exhaust, sleeve valve means for controlling said ports, and a piston provided with a cut-away portion adapted for cooperation with one of said sleeve ports. 115

85 15. In an engine of the sleeve valve type having a cylinder ported for intake and exhaust, sleeve valve means for controlling said ports, and a piston provided with a plurality of cut-away portions spaced circumferentially about the piston for cooperative operation with some of said ports. 125

90 16. In an engine of the sleeve valve type having a cylinder ported for intake and exhaust, sleeve valve means having intake and exhaust ports cooperating with the said cylinder intake and exhaust ports, and a piston cooperating therewith and operable longitudinally of the cylinder, said piston having an outer edge normally extended beyond one of said sleeve ports in its outer limit of travel and provided with a cut-away portion adapted for cooperative operation with the sleeve port whereby to provide a communicating 130

- passage between said sleeve port and cylinder interior.
17. In an engine of the sleeve valve type having a cylinder ported for intake and exhaust, sleeve valve means having intake and exhaust ports cooperating with said cylinder intake and exhaust ports, and a piston cooperating therewith and having a cut-away portion adapted for cooperative operation with one of said sleeve ports. 80
18. In an engine of the sleeve valve type having a cylinder ported for intake and exhaust, sleeve valve means having intake and exhaust ports cooperating with said cylinder intake and exhaust ports, and a piston cooperating therewith and having a plurality of cut-away portions spaced circumferentially about the piston, each cut-away portion being adapted for cooperative operation with one of said sleeve ports. 85
19. In an engine of the sleeve valve type having a cylinder ported for intake and exhaust, a ported single sleeve valve means associated therewith and having a combined reciprocating and oscillating motion with respect to the cylinder and sleeve axes in controlling the cylinder ports, said sleeve valve means opening said cylinder intake port prior to engine intake, and a piston cooperating with said sleeve valve means to mask said intake port and thereby close the communication between the cylinder intake port and engine cylinder during a portion of the time said sleeve intake port is in registration with the cooperating cylinder intake port whereby to control engine intake, said piston provided with means providing for engine exhaust during the opening of said cylinder intake port and prior to engine intake. 90
20. In an engine of the sleeve valve type having a cylinder ported for intake and exhaust, sleeve valve means for controlling said ports, and a piston provided with an outer peripheral edge having a cut-away portion cooperating with one of said sleeve ports. 95
21. In an engine of the sleeve valve type having a cylinder ported for intake and exhaust, a single sleeve valve means having a combined oscillating and reciprocating movement with respect to the sleeve and cylinder axes for controlling said ports, and a piston operable in timed relation with said sleeve valve, the outer peripheral edge of said piston having a cut-away portion cooperating at a predetermined time in the engine cycle with one of said sleeve ports. 100
22. In an internal combustion engine of the sleeve valve type having a cylinder ported for intake and exhaust, a piston operable in said cylinder, sleeve valve means of the combined oscillating and reciprocating type for controlling said cylinder intake and exhaust ports, said sleeve valve means being timed in operation with respect to piston travel whereby to open the cylinder intake port at an appreciable time interval before the piston reaches its outermost limit of travel, said piston cooperating with said sleeve valve means and operable to control the beginning of the engine intake and to open same subsequently to the opening of said cylinder intake port by said sleeve valve means. 105
23. In an internal combustion engine of the sleeve valve type having a cylinder ported for intake and exhaust, a piston operable in said cylinder, sleeve valve means of the combined oscillating and reciprocating type for controlling said cylinder intake and exhaust ports, said sleeve valve means being timed in operation with respect to piston travel whereby to open the cylinder intake port at an appreciable time interval before the piston reaches its outermost limit of travel and prior to closing of said cylinder exhaust port, and means cooperating with said sleeve valve means for masking said intake port substantially during the latter portion of the engine exhaust cycle and operable to control the beginning of the engine intake, said engine intake being opened subsequently to the opening of the cylinder intake port by said sleeve valve means. 110
24. In an internal combustion engine of the sleeve valve type having a cylinder ported for intake and exhaust, a piston operable in said cylinder, sleeve valve means having a movement axially of the cylinder for controlling the cylinder intake and exhaust ports, said cylinder intake port being located near the outer end of the cylinder and adjacent the outermost position of travel of said piston, said sleeve valve means being timed in operation with respect to piston travel whereby to open said cylinder intake port while said piston is travelling outwardly of the cylinder, said piston masking said cylinder intake port at least until said piston reaches its outermost position of travel and being operable to control the beginning of engine intake by unmasking said sleeve intake port subsequently to the opening of said cylinder intake port by said sleeve valve means. 115
